UNITED STATES PATENT OFFICE

160,885

CHILD'S VEHICLE

La Von I. Powell, Denver, Colo.

Application October 20, 1949, Serial No. 5,585

Term of patent 7 years

(Cl. D34—15)

To all whom it may concern:

Be it known that I, La Von I. Powell, a citizen of the United States of America, residing at Denver, in the county of Denver and State of Colorado, have invented a new, original, and ornamental Design for Child's Vehicle, of which the following is a specification, reference being had to the accompanying drawing, forming part hereof.

In the drawing:

Fig. 1 is a side view of a child's vehicle, showing my new design;

Fig. 2 is a top view thereof;

Fig. 3 is a front view thereof; and

Fig. 4 is a rear view thereof.

I claim:

The ornamental design for a child's vehicle, as shown.

LA VON I. POWELL.
